UNITED STATES PATENT OFFICE.

HENRY B. PETIT, OF DETROIT, MICHIGAN, ASSIGNOR TO GEORGE M. HOLLEY, OF DETROIT, MICHIGAN.

VAPORIZING MANIFOLD.

Application filed April 22, 1927. Serial No. 185,692.

The object of this patent is to improve the heat control of a vaporizer intended to be used in conjunction with internal combustion engines. It has heretofore been found extremely difficult to get any adequate control of the heat. The most that could be accomplished was to vary the ultimate mixture temperature 10° or 20° F., which is not a sufficiently large difference to take care of changes in the atmospheric temperature of over 100° F., which change is not at all unusual.

The specific object of this invention is to improve vaporizers of the type shown in Patents #1,562,670 and #1,547,474, in which a rich mixture is drawn over a relatively thin metal plate surface which is heated on the other side by the exhaust gases.

Figure 1 shows the manifold in elevation.

Figure 2 shows a cross sectional elevation 20 on the plane 2—2 of Figure 1.

Figure 3 shows an elevation of Figure 2.

Figure 4 shows a cross sectional plan view on plane 4—4 of Figure 1.

Figure 5 shows a cross sectional plan view 25 on plane 5—5 of Figure 1.

Figure 6 shows a cross sectional elevation on the plane 2—2 of Figure 3, showing the upper part of the mixing chamber. This view illustrates the mixing chamber in use 30 on Fordson tractors.

In the figures, A is the exhaust manifold, cast integral with which is the inlet manifold B. An opening O is provided in the exhaust manifold which is covered by a hollow cover 35 C. This cover is provided with an outlet D which corresponds to the outlet 36 of the Patent #1,562,670, and through which a heated rich mixture is drawn into the inlet manifold of the engine through the pipe T, 40 the rich mixture entering into the mixing chamber S through the outlet U. The mixture outlet is controlled by the throttle valve V and the cold air is admitted through the pipe W. An automatic valve X corresponding 45 to the valve 39 of Welch is provided in the entrance, being diluted enroute by the addition of the main air which is unheated in the mixing chamber.

E is the outlet from the exhaust manifold 50 which is controlled by a throttle valve F. G is the exhaust bypass formed in the hollow cover C. H J are two sheet steel plates clamped between the exhaust manifold A and the cover C. A partition K is provided in 55 the exhaust manifold A which causes the exhaust gases discharge from the cover to the

exhaust gases to follow the path, shown by the arrows in Figure 2, when the throttle F is closed. Liquid fuel is admitted to the path between the two plates H and J through a nozzle (not shown) which projects through 60 the opening L. The nozzle is fed from a float chamber (not shown) which is bolted to the cover C by the tapped holes Q Q.

Air for aspirating this fuel is admitted through the tube M, which communicates 65 with the horizontal passage N, which passage communicates with the narrow space between J and H. The passage G communicates through a port P with the exhaust outlet E on the atmospheric side of the butterfly valve 70 F, thus on closing the valve F the passage G forms an auxiliary path through which the exhaust gases can escape to the atmosphere and at intermediate position of F it forms an auxiliary path.

Operation.—When the engine is first started the valve F is closed, thereby causing the exhaust gases to follow the path indicated by the arrows in Figure 2. Exhaust gases therefore are diverted by the partition K in 80 the direction of the valve F and are then caused to back up and flow on the other side of K, past the plate J and then through G and back to the outlet F.

When the engine warms up the throttle F 85 is opened gradually and the exhaust gases are thereby permitted to escape more and more directly through the outlet E. Owing to the pulsating nature of the flow of the exhaust gases, however, the heating effect on the 90 plates J and H, upon the fuel passing from L up between the plates, is never wholly eliminated, because exhaust gases always back up into the passage G, for example, and also between J and K. The heating effect of 95 course is greatly diminished and thus an effective heat control is secured.

What I claim is:—

1. A vaporizing manifold comprising an exhaust manifold, a partition therein, an opening therein opposite said partition, a cover forming a closure therefor, a vaporizing element interposed between said cover and said opening, a fuel and air entrance thereto and a vapor outlet therefrom, said cover having an exhaust bypass therethrough adapted to heat one side of the vaporizing metal element, an exhaust outlet from the manifold, a passage through which the 100 exhaust gases discharge from the cover to the 105

outlet, a valve cooperating with said partition located in the exhaust outlet on the engine side of the bypass outlet and adapted in one position to force the exhaust gases to flow on both sides of the vaporizing element, and adapted in another position to permit the exhaust gases to escape directly to the exhaust outlet.

2. A vaporizing manifold comprising an exhaust manifold, a partition therein, an opening therein opposite said partition, a cover forming a closure therefor, a vaporizing element interposed between said cover and said opening, comprising two parallel plates separated from each other, a fuel and air entrance thereto and a vapor outlet therefrom, said cover having an exhaust bypass therethrough adapted to heat one side of the vaporizing metal element, an exhaust outlet from the manifold, a passage through which the exhaust gases discharge from the cover to the outlet, a valve co-operating with said partition located in the exhaust outlet on the engine side of the bypass outlet and adapted in one position to force the exhaust gases to flow on both sides of the vaporizing element,

and adapted in another position to permit the exhaust gases to escape directly to the exhaust outlet.

3. A vaporizing manifold comprising an exhaust manifold, a partition therein, an opening therein opposite said partition, a cover forming a closure therefor, a vaporizing element interposed between said cover and said opening, comprising two thin parallel metal plates separated from each other, a fuel and air entrance thereto and a vapor outlet therefrom, said cover having an exhaust bypass therethrough adapted to heat one side of the vaporizing metal element, an exhaust outlet from the manifold, a passage through which the exhaust gases discharge from the cover to the outlet, a valve co-operating with said partition located in the exhaust outlet on the engine side of the bypass outlet and adapted in one position to force the exhaust gases to flow on both sides of the vaporizing element, and adapted in another position to permit the exhaust gases to escape directly to the exhaust outlet.

In testimony whereof I affix my signature.
HENRY B. PETIT.
